CLAIM

(**) Term: **14 Years**

The ornamental design for a vehicle seat, as shown and described.

(21) Appl. No.: **29/499,491**

DESCRIPTION

(22) Filed: **Aug. 15, 2014**

FIG. 1 is a front, top and right side perspective view of a vehicle seat showing our new design;

(30) **Foreign Application Priority Data**

FIG. 2 is a front elevational view thereof;

Feb. 27, 2014 (JP) 2014-004101

FIG. 3 is a rear elevational view thereof;

(51) **LOC (10) Cl.** **06-01**

FIG. 4 is a right side elevational view thereof;

(52) **U.S. Cl.**

FIG. 5 is a left side elevational view thereof;

USPC **D6/716.4**

FIG. 6 is a top plan view thereof;

(58) **Field of Classification Search**

FIG. 7 is a bottom plan view thereof;

USPC D6/356, 716, 716.1, 716.4, 611;

FIG. 8 is an enlarged fragment view taken along line 8-8 in

180/9.23; 244/122

FIG. 2 thereof;

CPC B60R 2011/0012; B60R 2011/0015; B60N

FIG. 9 is an enlarged fragment view taken along line 9-9 in

2/00; B60N 2/24; B60N 2/242; B60N

FIG. 4 thereof;

2/44

FIG. 10 is an enlarged fragment view taken along line 10-10

See application file for complete search history.

in FIG. 8 thereof; and,

(56) **References Cited**

FIG. 11 is a cross-sectional view taken along line 11-11 in

The dash-dot-dash broken lines represent the boundary lines of the claimed design.

The lightweight dashed broken lines shown in the drawings outside of the dash-dot-dash boundary lines represent portions of the vehicle seat that form no part of the claimed design.

The heavyweight dashed broken lines shown in the drawings within the dash-dot-dash boundary lines illustrate stitching

and do form a part of the claimed design.
